US00D787160S

(12) **United States Design Patent** (10) **Patent No.:** **US D787,160 S**
(45) **Date of Patent:** **** May 23, 2017**

(54) **GARMENT**

(71) Applicant: **Milwaukee Electric Tool Corporation**,
Brookfield, WI (US)

(72) Inventors: **Jason R. Crowe**, Seattle, WA (US);
Timothy Janda, Elkhorn, WI (US);
Kim Brannock, Bend, OR (US); **Jerry**
Gundersen, Bainbridge Island, WA
(US)

(73) Assignee: **MILWAUKEE ELECTRIC TOOL**
CORPORATION, Brookfield, WI (US)

(**) Term: **15 Years**

(21) Appl. No.: **29/542,035**

(22) Filed: **Oct. 9, 2015**

(51) LOC (10) Cl. **02-02**

(52) U.S. Cl.

USPC **D2/828; D2/750**

(58) **Field of Classification Search**

(57) **CLAIM**

We claim the ornamental design for a garment, as shown and
described.

DESCRIPTION

FIG. 1 is a front perspective view of a garment, such as a
hoodie.

FIG. 2 is a rear perspective view of the garment shown in
FIG. 1.

FIG. 3 is a front view of the garment shown in FIG. 1.

FIG. 4 is a rear view of the garment shown in FIG. 1.

FIG. 5 is a right side view of the garment shown in FIG. 1;
and,

FIG. 6 is a left side view of the garment shown in FIG. 1.
The stitching shown in broken lines forms a part of the
claimed design.

1 Claim, 6 Drawing Sheets
